JAMES J. COOMBER, OF HOBOKEN, NEW JERSEY, ASSIGNOR TO MUNSON SUPPLY COMPANY, OF NEW YORK, N. Y., A CORPORATION OF NEW YORK.

PNEUMATIC CUSHION FOR KEYS.

1,397,574.

Specification of Letters Patent.

Patented Nov. 22, 1921.

Application filed March 14, 1921. Serial No. 452,159.

To all whom it may concern:

Be it known that I, JAMES J. COOMBER, a citizen of the United States, and resident of Hoboken, in the State of New Jersey, have 5 invented certain new and useful Improvements in Pneumatic Cushions for Keys, of which the following is a specification.

This invention relates to pneumatic cushions for keys, pertaining more particularly 10 to cushion structures for typewriting keys.

Cushioning structures for this purpose have generally embodied a cushioning member of resilient material, such as rubber, and a securing member, generally metallic, the 15 latter member being generally formed with a cavity to receive a portion of the cushioning member, the upper edge of the cavity walls having an annular inturned edge adapted to enter a properly-positioned annular groove formed in the cushioning member, thus tending to retain the cushioning member in position on the securing member. The cushioning member, in some cases, is formed with an under cavity—leaving an 25 annular portion located below the edge of the securing member—the presence of the under cavity permitting the desired “give” to the top of the cushion when the latter is struck in the typing operation.

30 While such structures have proved efficient in service, they have certain disadvantages which tend to affect the service conditions of the cushions. For instance, the presence of the groove so decreases the 35 thickness of the walls of the cushion as to make the cushion structurally weak at this point, especially in use where the difference in resiliency between the outer edge of the top surface and the center tends to permit of 40 relative movement such as tends to break down the weak connection at this point. In addition, the annular portion seated in the securing member cavity—located below this groove—may also be affected when assembling the two members, since the weak connection may not force this portion—more or less contracted to permit insertion into the cavity—to spread out properly after the edge has entered the groove, thereby preventing 45 the desired location of this annular portion and tending to produce a formation which in itself may tend to affect the wearing or lasting qualities of the cushion through the repeated striking of the cushion in use.

50 Furthermore, the presence of the groove and

this weak connection tends to reduce the resilient action of the top of the cushion, since the part of the annular seated portion of the cushion which extends inwardly beyond the edge is so small as to offer little aid in the 60 support of the top, so that the resistance against damage of the top is entirely dependent on the top itself—to increase the thickness of the annular portion would restrict the area of the cushion cavity and decrease 65 the desired resiliency.

The present invention is designed to overcome these disadvantages by eliminating this source of weakness of the cushioning member, and in addition, by strengthening the 70 annular portion through a reinforcing element, thus avoiding the conditions which inherently act to decrease the life of the cushioning member and meet the conditions of heavy service.

75 Other objects are to provide a construction which is simple and efficient in operation, neat and attractive in appearance, durable in construction, and which can be manufactured at a relatively low cost.

80 To these and other ends, the nature of which will be readily understood as the invention is hereinafter disclosed, said invention consists in the improved construction and combination of parts, hereinafter fully 85 described, illustrated in the accompanying drawings, and more particularly pointed out in the appended claims.

85 In the accompanying drawings, in which similar reference characters indicate similar 90 parts in each of the views,—

95 Figure 1 is a view partly in elevation and partly in section showing one embodiment of the invention as applied to a typewriter key.

Fig. 2 is a perspective view of the complete cushioning structure of Fig. 1.

Fig. 3 is a central vertical section of the cushioning member.

Fig. 4 is a horizontal sectional view taken 100 on line 4—4 of Fig. 3.

105 In the present embodiment the securing member 10 is formed with two cavities, this being provided by a partition 10^a between the upper and lower planes of the member, that portion of the member above the partition being of double thickness, the portion below the partition being of single thickness and being formed with an indentation 10^b which acts to maintain the member in posi- 110

tion on the key 11. This general formation may be provided in any suitable manner, as by a dieing operation.

As will be seen the doubled or upper portion is given somewhat of a curved configuration in cross section toward the upper edge, thus giving a lip formation of decreased diameter, the lip being more or less rounded by the doubling of the material in 10 the formation of the securing member or cap. This showing is more or less illustrative so far as the curvature is concerned, the particular form which the portion below the lip may take being a matter of design, 15 the curved form, however, lending itself to an easier securing operation and being less damaging to the cushion member.

The cushioning member 12 is preferably of the general formation shown in Fig. 3, 20 embodying the top or crown portion 12^a, the body or annular portion 12^b, and if desired, the web formation 12^c—shown more particularly in Fig. 4,—and shown as located in the general cavity of the member 25 and preferably of less depth than portion 12^b. The crown portion is of greater diameter than body portion 12^b, thus providing a simple shoulder effect, this shoulder, when the members are assembled, practically resting on the cap lip. Portion 12^b is substantially of equal thickness cross-sectionally throughout its vertical height, so that there is no weakened formation present below the crown-portion.

35 Portion 12^b preferably carries a reinforcing element 13 of suitable type, this element being shown as an annular member, preferably metallic, embedded within the portion, and with its upper edge spaced from 40 and below the plane of the line of juncture of the crown and annular portions. The element is preferably provided with inwardly projecting or inturned portions 13^a which tend to maintain the position of the 45 element within the annular portion. Element 13 is preferably molded in the annular portion when the cushion is being manufactured.

In assembling the two members, the annular portion of the cushion is slightly compressed to permit it to pass within the lip of the cap, where the lip is provided in advance of the assembly. Obviously, the cap may have the doubled portion uncurved 55 and then bent inward to produce the lip effect after the cushion has been seated. In the assembly, however, the lip is located between the planes of the body portion and the upper edge of element 13 and therefore 60 within the non-reinforced zone of the annular portion, so that compression of the latter can be readily had, as indicated in Fig. 1, the compression being effective between the crown portion and the reinforced zone of 65 the annular portion, said latter zone not

only insuring that the normal configuration of the confined portion will be properly maintained, but offering a structural formation which tends to prevent ready withdrawal from its seating cavity. As a result, 70 the cushion will remain properly seated even under extreme service conditions. And since the unreinforced zone is not weakened structurally there is little or no liability of the crown portion being broken from this 75 annular portion, especially since the lip is of a configuration which offers no cutting action on the cushion material. Furthermore, the pressure provided in striking the cushion is less liable to damage the formation at the lip plane since the annular portion itself carries a more or less rigid element operative to aid in resisting this pressure so that there is less likelihood of this 80 pressure tending to carry the crown portion 85 downward beyond the lip.

Obviously, the general configuration of the cushion member is simplified by the changes made, being a construction easily molded. The cap formation can be readily 90 produced by a die operation, so that the completed construction can be manufactured at relatively low cost.

While I have herein shown and described a preferred form of construction, it will be 95 readily understood that changes or modifications therein may be found desirable or essential in meeting the various exigencies of use, and I desire to be understood as reserving the right to make any and all 100 such changes or modifications as may be found desirable or essential, in so far as the same may fall within the spirit and scope of the invention as expressed in the accompanying claims when broadly construed.

Having thus described my invention, what I claim as new is:—

1. As a new article of manufacture, a pneumatic cushion for keys comprising a resilient cushioning member adapted for 110 attachment to a securing member, the said cushioning member including a top or crown portion and a depending body portion, the said depending portion being provided with a rigid reinforce in the body 115 thereof adapted for coöperation with the said securing member.

2. A pneumatic cushion for keys comprising a resilient cushioning member, and a securing member, said securing member 120 having a cavity to receive the cushioning member and a lip to maintain the cushioning member in seated position, said cushioning member having a rigid reinforce tending to maintain the seated condition of the 125 cushioning member.

3. A pneumatic cushion for keys comprising a resilient cushion member, and a securing member, said securing member having a cavity to receive the cushion member 130

and a lip to maintain the cushion member in seated position, said cushion member having a rigid reinforce below the plane of the lip tending to maintain the seated condition 5 of the cushion member.

4. A pneumatic cushion for keys comprising a resilient cushion member, and a securing member, said securing member having a cavity to receive the cushion member 10 and a lip to maintain the cushion member in seated position, said cushion member having an integral annular portion extending within the cavity and adapted to contact with cavity walls, said portion carrying a rigid reinforce.

5. A pneumatic cushion for keys comprising a resilient cushion member, and a securing member, said securing member having a cavity to receive the cushion member 20 and a lip to maintain the cushion member in seated position, said cushion member having an integral annular portion extending within the cavity and adapted to contact with cavity walls, said portion having an annular metallic element embedded therein 25 to constitute a reinforce therefor.

6. A pneumatic cushion for keys comprising a resilient cushion member, and a securing member, said securing member having a cavity to receive the cushion member 30 and a lip to maintain the cushion member in seated position, said cushion member having an integral annular portion extending within the cavity and adapted to contact with cavity walls, said portion having an annular metallic element embedded therein 35 below the plane of said lip to constitute a reinforce therefor.

7. A pneumatic cushion for keys comprising a resilient cushion member, and a securing member, said securing member having a cavity to receive the cushion member 40 and a lip to maintain the cushion member in seated position, said cushion member having an integral annular portion extending 45 within the cavity and adapted to contact with cavity walls, said portion having an

annular metallic element embedded therein to constitute a reinforce therefor, said element having at least one laterally-projecting portion for maintaining the position of the 50 element.

8. A pneumatic cushion for keys comprising a resilient cushion member, and a securing member, said securing member having a cavity to receive the cushion member and 55 a lip to maintain the cushion member in seated position, said cushion member having an integral annular portion extending within the cavity and adapted to contact with cavity walls, said portion having an 60 annular metallic element embedded therein to constitute a reinforce therefor, said element having at least one laterally-projecting portion at its upper edge for maintaining the position of the element.

9. A pneumatic cushion for keys comprising a resilient cushion member, and a securing member, said securing member having a pair of cavities separated by a partition intersecting the member axis intermediate 70 the opposite ends of the member, the walls of one of said cavities being of double thickness with the marginal edge shaped to form an annular lip of a diameter smaller than the diameter of the said walls, said cushion member being seated in said cavity and 75 maintained in position by the lip.

10. As a new article of manufacture, a pneumatic cushion for keys comprising a resilient cushioning member adapted for attachment to a securing member, the said 80 cushioning member including a top or crown portion and a depending annular body portion of a diameter less than the crown portion, the said depending portion being provided with a rigid annular 85 reinforce in the body thereof adapted for co-operation with the said securing member.

Signed at Hoboken, in the county of Hudson and State of New Jersey, this 5th day of March, A. D. 1921.

JAMES J. COOMBER.
